ATTORNEY.

UNITED STATES PATENT OFFICE

LOUIS ROTELLA, OF MONTREAL, QUEBEC, CANADA

GASOLINE FILTER

Application filed October 29, 1928. Serial No. 315,745.

The invention relates to a gasoline filter, as described in the present specification and illustrated in the accompanying drawings that form part of the same.

5 The invention consists essentially of the novel features of construction pointed out in the claim for novelty following a description containing an explanation in detail of an acceptable form of the invention.

10 The objects of the invention are to prevent water, dirt or other matter from entering the feed inlet of combustion or other engines using gasoline as their fuel; to eliminate a source of constant trouble in engines 15 due to irregularity of feed and consequently poor mixture entering their inlet manifolds; to insure a steady supply of strained gasoline within a gasoline reservoir in a tank and ready to be taken out; to add a measure 20 of safety to the motorists and others who procure their fuel from wayside stations and other places where the supply is not always pure; to furnish a device that will be constantly in operation and will prevent injury 25 to the motor and inconvenience to the motorists; and generally to provide a durable and efficient filter gasoline tank at a minimum cost.

In the drawings Figure 1 is a rear view of a 30 gasoline tank partly broken away to disclose the filter.

Figure 2 is a vertical section of the gasoline filter showing a feed pipe inserted therein.

Figure 3 is a cross sectional view of the 35 filter taken on the line 3—3 in Figure 2.

Like numerals of reference indicate corresponding parts in the various figures.

Referring to the drawings the gasoline filter is indicated by the numeral 10 and is 40 formed of a cage 11 having the several vertical apertures 12 divided off from one another by the bars 13 extending from the upper and lower ends 14 and 15 of the cage walls, said upper and lower ends being circular in cross section.

A chamois 16 is wrapped around the cage 11 and covers the several apertures 12 and overlaps at the ends 14 and 15 of the cage walls and is secured thereto by a ring 17 and 50 a plate 18 respectively.

The ring 17 and the plate 18 have the flanges 19 and 20 with the holes 21 and 22 which correspond with the threaded recesses 23 and 24 at the upper and lower ends 14 and 15 of the cage walls and are secured together by means of the screws 25.

The cage 11 is inserted into the tank 26 and is held thereto by the screw mounting 27 secured to the tank and having the ledge 28 supporting the flange 19 of the ring 17 and 55 between which the gasket 29 is inserted. An externally threaded cover or cap 30 having the central orifice 31 engages with the screw nut 27 and completes the fastening for holding the cage in the tank.

The feed pipe 32 extends through the orifice 31 centrally into the cage 11 and is connected at the other end to the carburetor of an engine or other device.

In the use of this invention the filter is 70 inserted in a gasoline tank of a vehicle and the gasoline in the tank flows through the chamois into the apertures of the cage and is thoroughly strained and is ready to be taken up into the feed pipe to the carburetor 75 and engine.

The construction of the filter gasoline tank may be varied in accordance with the use in which it is applied as in gasoline pumps, gasoline reserve tanks and other 80 places where gasoline is either stored or is being used.

What I claim is:—

A gasoline filter comprising a cap for retaining the filter in position, a cage having 85 openings in the sides, and a chamois wrap- per therearound and overlapping the ends, a ring and plate engaging the ends of the cage and having bosses engaging with the inner portion of the cage ends and screw-held 90 therein and a pipe outlet from the cage through the cap.

Signed at Montreal, Canada, this 20th day of September, 1928.

LOUIS ROTELLA. 95
